UNITED STATES PATENT OFFICE.

LAWRENCE O. BEARD, OF LANCASTER, PENNSYLVANIA.

SECONDARY CLOCK.

1,251,171.

Specification of Letters Patent.

Patented Dec. 25, 1917.

Application filed August 6, 1915. Serial No. 44,111.

To all whom it may concern:

Be it known that I, LAWRENCE O. BEARD, a citizen of the United States, and a resident of Lancaster, in the county of Lancaster and State of Pennsylvania, have invented certain new and useful Improvements in Secondary Clocks; and I do hereby declare the following to be a full, clear, and exact description of the invention, such as will enable others skilled in the art to which it appertains to make and use the same.

This invention relates to improvements in secondary clocks and more particularly to electrically controlled escapement mechanism therefor,—objects of the invention being to so construct the mechanism as to reduce wear to a minimum; to insure accuracy of operation; to obviate liability of the working parts getting out of proper adjustment, and to simplify the construction and number of separate parts of an escapement mechanism of the type to which my invention relates.

A further object is to so construct the escapement that the locking pins or pallets on the verge shall operate in such manner that one of said pins or pallets will prevent the escapement wheel moving forwardly more than one step or tooth at a time while the driving means is moving forwardly and lock said wheel when the latter has been moved a full step, and so that the other pin or pallet shall perform a like function when the driving means has moved backwardly.

With these and other objects in view, the invention consists in certain novel features of construction and combinations of parts as hereinafter set forth and pointed out in the claims.

In the accompanying drawings; Figure 1 is a front elevation of a clock movement (with a portion of the frame removed) showing an embodiment of my invention, and Fig. 2 is a plan view.

1 represents the frame of a clock movement of the kind employed in secondary clocks, and 2 indicates the escapement wheel of such movement.

30 An arbor 3 is located in the upper portion of the frame 1, and a lever 4 having a general L-shape, is loosely mounted at the juncture of its upright and horizontal portions on said arbor. The depending portion of the lever 4 is made with laterally projecting arms to form a verge 5 having pins or pallets 6 near the free ends of said arms for coöperation with the escapement wheel 2, said pins or pallets preferably being made tapering or wedge-shaped so that a flat face 60 of each pin will engage the flat faces of the teeth of the escapement wheel and hold the latter positively against movement.

The horizontal arm 7 of the lever 4 is provided with a weight 8, and below this weighted arm, an electro-magnet 9 is secured to the frame 1,—said electro-magnet being included in a suitable electric circuit with mechanism of a master clock (not shown) as is usual. An armature lever 10 for said magnet is pivotally supported in the frame 1 as indicated at 11, and carries a cam-arm 12 disposed directly under and adapted to engage the weighted arm 7 of lever 4 for raising said arm.

75 The verge 5 which constitutes the depending portion of the lever 4, carries a gravity pawl 13 adapted to engage the escapement wheel for propelling the same, and a gravity dog 14 is hung loosely on the arbor 3 so as 80 to engage the escapement wheel and prevent possibility of retrograde movement thereof.

The armature lever of the magnet carries cushions 15 and 16 to be engaged by the weighted arm 7 of lever 4 and thus reduce 85 noise to a minimum.

During the operation of the device,—when the magnet is energized, engagement of the cam-arm 12 of its armature lever 10 with the arm 7 of lever 4 will cause the 90 weighted arm 7 to be raised and so move the lever 4 that the gravity pawl 13 carried by the verge-portion 5 of said lever will move backwardly to position to engage the escapement wheel at the rear end of the 95 throw of said pawl, and so that the forward pallet 6 will engage against a tooth of said wheel and prevent possibility of forward movement thereof at this time. When the magnet is deenergized so as to release the 100 armature lever, the weighted arm 7 of lever 4 will drop by gravity and cause said lever to turn on its pivotal mounting, thus carrying the verge-portion 5 of said lever forwardly, in the arc of a circle, and the driving pawl 13, engaging a tooth of the escapement wheel, will cause said wheel to move forwardly one step. When the verge is thus being moved forwardly, the forward pin or pallet 6 will promptly leave the face of the 110 tooth with which it had engaged and freely move out from between two teeth without

conflict with them, and as the verge completes its forward movement, the rear pin or pallet 6 will move in between two teeth of the wheel and into engagement with one of them, thus locking the wheel against further forward movement. During the time that the wheel is being moved forwardly, the pallets will be successively free from contact with the teeth of said wheel, but at all times, 10 one of the pallets will be between teeth of the ratchet wheel.

My improvements comprise but few parts which are relatively movable, so that the mechanism is not subjected to excessive 15 wear and is not liable to get out of adjustment, but will operate accurately and with certainty.

Slight changes might be made in the details of construction of my invention without departing from the spirit thereof or limiting its scope and hence I do not wish to restrict myself to the exact details herein set forth.

Having fully described my invention what 25 I claim as new and desire to secure by Letters-Patent, is:

1. In a clock, the combination with an escapement wheel, of a lever forming in a 30 unitary structure a weighted arm and a verge arm, pallets carried by the verge arm to coöperate with said wheel, a driving pawl carried by the verge arm and coöoperating with said wheel to propel the same by the action of the weighted arm of said lever, 35 electromagnetic means for moving said lever intermittently in a direction to withdraw the driving pawl, and means for preventing retrograde movement of said wheel.

2. In a clock, the combination with an 40 escapement wheel, of a lever forming in a unitary structure, a weighted arm and a verge arm, pallets carried by said verge arm

to coöperate with said wheel, a driving pawl carried by said verge arm to propel the wheel by the action of the weighted arm, an 45 electro-magnet, an armature lever, an arm on said armature lever located under said weighted arm to raise the same and move said first-mentioned lever in a direction to withdraw the driving pawl, and means for 50 preventing retrograde movement of said wheel.

3. In a clock, the combination with an escapement wheel, of a verge having pallets near respective ends thereof for alternate 55 coöperation with the escapement wheel to lock the same, a driving pawl for the escapement wheel, carried by said verge, a gravity device for moving the verge in a direction to actuate the verge and driving pawl to propel the escapement wheel, electro-magnetic means for moving the verge in the other direction, and means for preventing retrograde movement of said wheel.

4. In a clock, the combination with a 65 frame, an escapement wheel, and an arbor in the upper portion of said frame, of a weighted lever mounted on said arbor, the depending portion constituting a verge arm 70 carrying pallets for locking the escapement wheel, a driving pawl carried by said verge arm, electro-magnetically operated means for moving said weighted lever in one direction, and a gravity dog hung on said arbor 75 and engaging the escapement wheel to prevent retrograde movement thereof.

In testimony whereof, I have signed this specification in the presence of two subscribing witnesses.

LAWRENCE O. BEARD.
